LAUNDRY PRESS GARMENT CLAMP

Stanley Marvin, San Francisco, Calif., assignor
to B. E. Witkin, Oakland, Calif.

Application August 23, 1937, Serial No. 160,491

6 Claims. (Cl. 38—12)

This invention relates to laundry presses of the type where an upper presser plate or buck is forced down upon a lower buck upon which the garment to be pressed or ironed is spread, and the invention has for its general object an improved clamping means for clamping the garment down on the lower buck.

The particular object of the invention is to provide an improved clamp for holding the lower or tail portion of a shirt clamped to the lower buck.

Other advantages of the invention will appear from the following description and accompanying drawing.

In the drawing:

Figure 1 is a side elevation of portion of a laundry press of the kind under consideration showing the rear or tail end of the lower buck, with my garment clamp in clamping position, and in dotted lines the unclamped position.

Figure 2 is an end elevation of the device as seen from line 2—2 of Figure 1.

Figure 3 is an enlarged cross sectional detail as seen from the line 3—3 of Figure 2.

Figure 4 is a view similar to that of Figure 3, but showing the clamping band swung to released position.

This apparatus, particularly for clamping the tail part of a shirt, is intended to cooperate with the apparatus of my copending patent application filed under Serial No. 126,859, on February 20, 1937, which clamps the neck band of the shirt, the two clamps holding the bosom of the shirt stretched smoothly on the lower buck for pressing by the upper one.

The invention may be generally described as a clamping strap which extends across the lower buck and is carried at the ends of a pair of arms pivotally mounted in such a manner that the strap can be swung from clamping position upward and backward clear over the tail end of the buck so as to be entirely out of the way in putting on or taking shirts from the buck. A feature of the invention is the provision of a hand crank or lever for operating the clamp so geared to the arms as to swing the band about 180 degrees of arc when the hand lever is moved but half this arcuate distance, or less depending on the gearing.

Other features are simplicity, ruggedness, and dependability of the construction.

In the drawing 1 is the lower buck which is transversely arched on its upper surface as at 1' to receive the shirts to be ironed, and is generally covered by suitable cloth or other padding not

shown. The buck is supported on the usual frame 2 above a work board or table 3.

The strap of the tail clamping device is shown at 4 and preferably is a thin flat band of non-corrodible metal bent to the form shown in Figure 2 so as to fit over the arched surface of the buck. The band 4 is secured, at its ends respectively, to the ends of two rigid cast metal levers 5 as by means of clips 6 held in place by screws 7. Arms 5 lie normally in horizontal position along opposite lower edges of the buck and are offset inwardly at 5' to bring their right hand ends closer to the supporting frame 2, and where they are formed with downwardly extending split hubs 8 which are firmly clamped to the outer ends of a horizontally extending shaft 9, and to which the hubs are also keyed or pinned as at 10 to prevent slipping relative to the shaft.

Shaft 9 is rotatably supported in bearing bosses 11 formed on the outer sides of a pair of cast bracket plates 12 secured to the buck frame as by bolts 13, and the plates project beyond the rear end of the frame 2 as best shown in Figures 1, 3 and 4 to accommodate the operating mechanism. A pinion gear 14 is secured to shaft 9 and meshes with a large gear 15 carried on a second shaft 16 which also extends through the bracket plates 12 and is rotatably supported in bearing bosses 17 formed thereon, and secured to shaft 16 adjacent the forward bracket plate 12 is a short lever or crank arm 18 slotted at 19 and engaging in its slot a pin or roller 20 projecting from the outer end of a similar lever or cam arm 21 secured to a stub shaft 22.

Stub shaft 22 is rotatably mounted in a relatively long hub 23 formed on the forward bracket plate, and secured to the outer end of the stub shaft is an operating crank 24 provided with a handle 25 for swinging the crank from the full line clamping position of Figure 1 about 90 degrees of arc to the dotted or released position indicated.

When in clamping position with band 4 tightly about the upper curved surface of the buck, lever 21 stands at right angles to lever 18 to lock the strap in place under pressure, and to provide adjustment of the locked position of the levers for various thickness of padding used on the buck gear 15 is not secured directly to shaft 16 but is secured by cap screws 26 to a flanged hub 27 which latter is firmly secured to the shaft. The cap screws pass through arcuate slots 28 in the flange to permit of any desired angular adjustment to give the pressure required at the locked or clamped position.

By the construction described the levers produce a powerful cam action as they move toward the locked position of Figure 3, and in releasing, lever 21 swings along the slot of lever 18 toward its shaft thus greatly speeding up the releasing movement, and swinging the arms 5 and clamping band through an arc of a half circle, or any further degree with suitable relation of the gears used.

10 The device is operated with but little effort on account of the cam lever effect, and when released the band 4 swings clear beyond the tail end of the buck and out of the way as indicated by the dotted position of Figure 1.

15 Having thus described my improved garment clamping device for laundry presses, what I claim is:

1. In a laundry press having a lower buck over which a garment is adapted to be spread for pressing, a clamping band arranged to extend transversely across the buck for clamping the garment on the buck, a pair of arms extending adjacent the sides of the buck and to which arms the ends of the band are secured, means pivotally mounting said arms for swinging the band upwardly from clamping position and rearwardly clear beyond the end of the buck, a manually operated lever arranged for swinging said arms, speed multiplying gear means operatively connecting said lever and said arms for increasing the motion of the arms relative to the lever, the connection between the gear means and said lever including a crank arm for turning the gear means and a connection from the crank arm to said lever arranged to bring increasing pressure on said crank arm and band as the band is swung to clamping position.

2. In the construction set out in claim 1, a cam operated by said lever, and said cam in turn

operating against said crank arm to turn the same and arranged to lock same with the band in clamping position.

3. In the construction set out in claim 1, a cam operated by said lever, and said cam in turn operating against said crank arm to turn the same and arranged to lock same with the band in clamping position, and means for adjusting the effective relation of said cam to said band.

4. In combination with the lower buck of a laundry press, a pair of bearing brackets firmly mounted below the buck, a pair of spaced shafts extending transversely under the buck and rotatably supported in said bracket, gears on said shafts gearing them together, a pair of arms secured to the outer ends of one of said shafts and extending along opposite edges of the buck, a shirt tail clamping band extending across the upper side of the buck with its ends secured respectively to said arms, an operating crank shaft rotatably supported adjacent the other of said shafts, and a slotted lever secured to the latter shaft engaged in its slot by a crank pin of the crank shaft, said slotted lever and crank pin arranged to bring a gradually increasing force upon the band as it is swung to clamping position by a force applied to the operating crank shaft.

5. In the construction specified in claim 4, means for adjusting the rotative relation of the arm carrying shaft to the slotted lever carrying shaft.

6. In the construction specified in claim 4, means for adjusting the rotative relation of the arm carrying shaft to the slotted lever carrying shaft, comprising a flanged hub secured to the latter shaft and to which the gear on said shaft is secured for rotative adjustment.

STANLEY MARVIN.
